TELEVISION SYSTEM

Le Roy Moffett, Baldwin, N. Y., assignor to Radio Corporation of America, a corporation of Delaware

Application March 31, 1942, Serial No. 436,936

8 Claims. (Cl. 178—7.2)

This invention relates to an improvement in television transmitting systems and more particularly to an improvement in arrangements for the reinsertion of the direct current picture signal component at the television transmitter.

In television transmitter equipment a transmitting tube is provided that functions to convert an optical light image into a series of picture signals. These picture signals constitute a very wide range of frequencies, the range being from substantially a direct current variation to frequencies of the order of six megacycles or more per second. The upper limit of the produced picture signal frequencies is a function of the subject matter scanned and the rate at which the scanning is performed. The relatively slow or low frequency potential variations are representative of the background or average brilliance of the picture rather than the detail thereof since, for example, in a picture that is predominantly black a certain component of low frequency may be produced whereas in a picture that is predominantly white a different low frequency and direct current component will be produced. Since the detail in the picture is represented by the relatively high frequencies, it is necessary that these high frequencies be transmitted to a receiver in order that the corresponding detail may be reproduced at the receiver. Likewise, inasmuch as the background or average brilliance of the picture is represented by the relatively low frequency potential variations and the direct current component, it is necessary that this portion of the picture signal series be transmitted in order to produce a proper image at the television receiver.

Inasmuch as the picture signals that are derived directly from the television transmitting tube are of relatively low intensity, it is necessary that the signals be subjected to several stages of amplification and, inasmuch as the use of alternating current coupled stages of amplification are considerably more commercially feasible than direct coupled amplifiers, the low frequency component and the direct current component of the picture signal series are blocked in the picture signal amplifier so that only frequencies above a certain predetermined frequency are passed through and amplified by the picture signal amplifier. In order that the low frequency component and the direct current component of the picture signal series may be transmitted, it is customary to reinsert the direct current component in the picture signal series just prior to the conventional radio frequency modulator tube. By direct coupling from the modulator tube it is then possible to

transmit the entire picture signal series. It has been found, however, that conventional methods of reinserting the direct current component do not insert that component at the proper value due to inherent losses in the usual direct current insertion circuit.

In order that the television receiving apparatus may be maintained in accurate synchronous operation with the television transmitter, a series of synchronizing impulses are transmitted, the synchronizing impulses occurring at both the horizontal and the vertical deflection rates. These synchronizing impulses are of relatively short duration and are interspersed with the picture signals so that they occur in synchronism with the deflections of the scanning cathode ray beam and are phased with respect to the deflection such that they are positioned in the picture signal series at instances corresponding to the return deflection of the scanning cathode ray beam in the television transmitter. Since no useful picture signals are generated at these intervals (or at periods corresponding to the scanning beam blanking interval), the insertion of the horizontal and vertical synchronizing impulses at such time does not interfere with the transmission of the picture signals and, furthermore, the transmission of the synchronizing impulses at such instances affords a desirable time to trigger or control deflection oscillators in the apparatus contained in the receiving set.

According to present standards of television transmission, the synchronizing signals are transmitted at full carrier output whereas signals representative of black in the picture are transmitted at about 75% of full carrier output. This variation in the intensity of the signals corresponding to black may vary $\pm 2.5\%$ from 75% of maximum power output. Signals representative of white in the picture are then transmitted at values representative of lesser degrees of modulation. Inasmuch as the synchronizing signals may always be transmitted at the same intensity there is generally no variation in the differential percentage of modulation in so far as the synchronizing signals are concerned as compared with black since the signals are transmitted at substantially maximum carrier they are generally referred to as extending in a blacker than black direction.

For the transmission of picture signals and in order to fix a predetermined reference point with respect to which the alternating current components of the picture signals are transmitted, the signal level of black in the picture (which cor-

responds to the signal strength of the pedestal or blanking signal upon which the synchronizing signals are positioned) is generally taken as a reference point. Then the alternating current axis of all of the alternating current components may be related to black in the picture. If, therefore, a picture is predominantly black the alternating current axis of the picture signals per se will be moved to a point more nearly adjacent the level represented by black than would be the alternating current axis of a picture that is predominantly white. In the absence of a direct current insertion circuit the alternating current component of the picture signals would not be positioned with respect to a chosen reference point with the result that all television images at the receiver would contain the same average amount of light regardless of the over-all brilliance or lack of brilliance of the original television picture. For example, in the absence of direct current insertion, a picture or scene at a beach where high intensity of light is encountered would appear grayish on the television receiver screen rather than predominantly light whereas a scene taken in a tunnel or darkened room would appear "washed out" or lighter than should be the case. The insertion of the direct current component therefore shifts the alternating current axis of the picture signals with respect to black in the picture in order to thereby transmit an indication of the proper background level so that appropriate circuits in the receiver may respond to that transmission to vary the bias between cathode and control electrode in the television reproducing tube to accordingly alter the average brilliance of the reproduced television image.

In presently used direct current insertion circuits, it has been found, as stated above, that the positioning of the alternating current axis of the picture signals is sometimes not absolutely accurate with the result that the proper direct current component is not in fact transmitted. This lack of absolutely correct insertion of the direct current component exists by reason of the inherent finite impedance of the diode or peak rectifier that is normally used for the insertion of the direct current component.

It is therefore one purpose of the present invention to provide a circuit for use at a television transmitter whereby the direct current component may be accurately reinserted in the picture signal series.

Still another purpose of the present invention resides in the provision of means whereby the position of the alternating current axis of the picture signals may be properly determined with respect to a reference point in accordance with the actual over-all brilliance of the particular television image scanned.

A still further purpose of the present invention resides in the provision of corrective networks whereby the inability of the usual direct current insertion diode to properly relate the alternating current axis may be compensated for to thereby introduce into the picture signal series the proper direct current level.

A still further purpose of the present invention resides in the provision of circuit means whereby both the alternating and the direct current components of a picture signal may be properly and accurately transmitted both as to frequency and relative intensities.

Still another purpose of the present invention resides in the provision of a corrective circuit for

introducing a variable correction component, the effectiveness of the correction component being a function of the average light intensity of the picture transmitted.

Various other purposes and advantages of the present invention will become more apparent to those skilled in the art from the following detailed description particularly when considered in connection with the drawings wherein:

Figure 1 represents one form of the present invention;

Figures 2, 3 and 4 represent modified forms of the present invention; and,

Figure 5 shows curves used in explaining the operation of the present invention.

Referring now to the drawings and particularly to Figure 1, there is shown a television picture signal amplifying tube 10 which includes a cathode 12, a control electrode 14 and anode 16. The cathode is connected to ground by way of a biasing resistance 18 while the control electrode is also connected to ground by grid resistor 20. When picture signals are applied to the terminals 22 the signals are impressed between cathode 12 and control electrode 14 of tube 10 by way of coupling condenser 24. The picture signals modulate the electron stream in the amplifying tube 10 with the result that varying degrees of anode current are permitted to pass through the anode load resistance 26. The potential appearing at the anode 16 of tube 10 is then impressed upon the control electrode 30 of tube 32 by way of coupling condenser 28.

The tube 32 preferably combines two triode elements including cathodes 34 and 36, control electrodes 30 and 38 and anodes 40 and 42. It is to be understood, of course, that two separate tubes may be used in place of the single "twin" tube. The cathodes 34 and 36 are connected together and are in turn connected to ground by way of potentiometer resistance element 44. The anodes 40 and 42 are also connected together and are in turn connected to terminal 46 to which a source of positive potential is applied.

For inserting the direct current component in the usual manner well known in the art, a direct current reinsertion circuit is represented schematically by the element 48. This device responds to the direct current component of the picture signal produced at the television transmitting tube and produces a control potential that is applied to the control electrode 30 of tube 32 so as to vary, at a relatively slow rate, the average potential of control electrode 30. The alternating current component of the picture signal series is impressed upon the control electrode 30 by way of condenser 28 and this component effects a rapid variation in the potential of the control electrode 30 of tube 32. In the circuit of the amplifier preceding the direct current inserter 48, only alternating current components are present and the picture signals vary between certain limits about a relatively fixed alternating current axis. Since, as stated above, coupling between amplifier stages is afforded by transformer or condenser means, the direct current component is lost and the average potential of the picture signals remains relatively constant. In the absence of the direct current inserter the picture signals would then be positioned about an A. C. axis spaced a relatively fixed amount with respect to the synchronizing and blanking signal series of the transmitted signal. When the direct current inserter 48 is included in the circuit the average potential of the control elec-

trode 38 of tube 32 is affected by the relatively slow potential variations and the direct current component to thereby shift the alternating current axis of the picture signal series. With the invention as so far described there will then appear across the cathode potentiometer resistance 44 potential variations representative of the alternating component and fairly representative of the direct current component. By reason of the impedance of the diode in the direct current inserter 48 the direct current level of the picture signals available from the potentiometer 44 are not absolutely correct.

Examples of various forms of diode direct current inserting circuits are shown and described in U. S. patent to Willans et al., No. 2,194,514, issued March 26, 1940.

To afford a complete and accurate understanding of the invention, reference is now made to Figure 5 wherein there is shown the grid voltage-plate current characteristic curve (E_g - I_b) of an amplifier tube. Below this curve, and associated therewith, is shown a small portion of a picture signal series wherein the synchronizing signals are represented at S, the blanking or pedestal impulses or signals at B and the picture signals by the rapid potential variations between blanking impulses. Furthermore, the synchronizing signals extend in a negative direction whereas white in the picture extends in a positive direction. This potential relationship is the potential of the voltage variations present at the cathode of tube 32 and at the control electrode of the same tube.

It will be noticed by inspecting Figure 5 that the tops of the synchronizing impulses or signals correspond to a certain fixed potential represented by the dotted line 62. Regardless of the picture content the synchronizing signals are always transmitted at this fixed potential. Likewise the height of the blanking impulses (that correspond to black in the picture) are also transmitted at a relatively fixed potential represented by the vertical dotted line 64. These two potentials are substantially fixed and the alternating current axis of the picture signals is transmitted at a value related to one or the other of these potentials by an amount determined by the average brilliance of the picture transmitted. In one instance, for example, picture signals such as shown at 66 may have an alternating current axis represented by the broken line 68 whereas picture signals such as those represented at 70 may have an alternating current axis represented by the broken line 72. (For purposes of explanation, a large variation is shown in the background level for the two adjacent picture lines, however, it is to be understood that in practice the variation in background content is relatively slow and in fact not appreciable between successive fields.) It is the purpose of the present invention to accurately position the alternating current axes 68 and 72, for example, with respect to the potentials 62 or 64 in accordance with the true direct current component of the originally produced picture signals. When the usual diode direct current inserter 48 alone is used it has been found that the position of the alternating current axes 68 and 72 are not accurately positioned but are, in fact, located generally a slight amount in the direction of black from their proper position. The inconsistency and variation in the inaccuracy in the positioning of the alternating current axis by the usual diode direct current inserter 48 is by reason of the fact that under conditions

of low background level such as represented by the picture signals shown at 66, the amount of current permitted to flow through the diode is relatively low so that the impedance of the diode inserter becomes appreciable. When the picture is predominantly white a larger amount of current is permitted to flow through the diode inserter with the result that the impedance of the diode is less predominant and a more accurate positioning of the alternating current axis results.

For compensating for the undesired and inaccurate positioning of the alternating current axis of the picture signal component, reference is again made to Figure 1 and particularly to the triode section shown in the right hand half of tube 32. Since the cathodes 34 and 36 are connected together the potential of the cathode 36 must vary exactly in accordance with the potential variations of cathode 34. The control electrode 38, however, is connected to a movable point 50 along potentiometer resistance 44 by a grid resistance 54. The control electrode 38 and the cathode 36 are also connected together by means of a filter condenser 56. The output from the tube 32 is derived from movable contact 52 associated with the potentiometer resistance element 44 in order that video or picture signal output may be derived from terminals 60. Since it is not desired that the electron stream flowing between cathode 36 and anode 42 be modulated at the rapid potential variations of the picture signals, the condenser 56 is provided so that the potential difference between control electrode 38 and cathode 36 may be made to vary at a relatively slow rate in accordance with the direct current component of the picture. Any appropriate low pass filter could as well be used. The anodic current flowing through this section of tube 32, however, is superimposed upon the anodic current flowing to anode 40 inasmuch as a common cathode resistance 44 is used for each triode section of the tube. The current flowing to the anode 42 therefore modifies the potential drop across the cathode resistance 44 produced by the anode current flowing to anode 40.

It will now be assumed that a picture or image signal series including synchronizing and blanking impulses is impressed upon the control electrode 30 with the synchronizing signals extending in a negative direction and with white in the picture extending in a positive direction. It will further be assumed that the picture or image signals represent an image that is predominantly black. Under these conditions the direct current inserter 48 will alter the potential of the control electrode 30 to shift the alternating current axis of the picture signal series but, as stated above, the shifted position may be slightly displaced from the position it should occupy. Since the applied picture or image signals represent an image that is predominantly black, the average potential of the control electrode 30 will be somewhat negative (near the negative potential represented by the blanking signals). As a result, the average current that is permitted to flow from cathode 34 to anode 40 will be relatively low so that a relatively low potential drop will be produced across the cathode resistance 44. Since the bias of the control electrode 38 is a function of the average current in the cathode resistance 44, and since under conditions of signals representing a predominantly black picture the current in resistance 44 is low, then the bias of con-

tral electrode 38 with respect to its cathodes 36 will be relatively low. As a result, an appreciable amount of current will be permitted to flow from the cathode 36 to the anode 42. This increased amount of current when superimposed upon the current flowing through cathode resistance 44 and anode 40 produces a further potential drop so that the alternating current axis of the picture signals available at the terminal 60 will be shifted slightly in a direction of white or away from the potential representing full black in the picture.

If, however, a picture signal series is applied to the control electrode 30 that corresponds to a picture that is predominantly white, then the average potential of the control electrode 30 will be less negative than in the case of a black picture with the result that more average current is permitted to flow to the anode 40. A larger potential drop will then be produced across cathode resistance 44. Increasing the bias on the control electrode 38 with respect to its cathode. This increased bias is not sufficient to cause cut-off of the tube and anode current continues to flow to anode 42. This current, when superimposed upon the current flowing through resistance 44 to anode 40 causes a shift in the alternating current axis of the signals as applied to the control electrode 30. This shift is in the same direction as in the above example where signals representative of a predominantly black picture were applied to control electrode 30. The additional shift in the alternating current axis as a result of the use of the direct current amplifier is greater for signals representing a predominantly white picture than for a predominantly black picture. The elements 36, 38 and 42 of tube 32 and the manner in which they are connected in the circuit constitute the elements of, and naturally function as, an amplifier for the direct current and low frequency components.

It may be seen, therefore, that from the terminal 60 may be derived a complete picture signal series in which the picture signals are correctly and properly related to the blanking and synchronizing signals, in so far as the position of their alternating current axis is concerned, in accordance with the intensity of the direct current component as produced by the television transmitting tube. The operation of the triode elements 36, 38 and 42 corrects for the inaccuracies in the position of the alternating current axis by the usual diode direct current re inserter 48. The effectiveness of the correction triode section may be controlled by positioning the movable contact 50 along the potentiometer 44. Full correction of course is obtained when the movable contact is positioned relatively adjacent the grounded end of resistance 44. The effect of the correction triode is reduced to a minimum when the movable contact is positioned near the cathode end of the resistance 44.

A modified form of the invention is shown in Figure 2 and elements corresponding to the elements of Figure 1 bear identical reference numerals. This circuit differs from the circuit shown in Figure 1 in that the cathodes 34 and 36 are not directly connected together but cathode 34 alone is connected to ground through the entire potentiometer resistance 44. The cathode 36 is connected to a point along the resistance 44 and the control electrode 38 is connected to ground by way of resistance 54 and biasing potential 55. Normally, the biasing potential of the source 55 may be such as to maintain the control electrode 38 negative with respect to ground,

however, under some circumstances and under conditions where the movable contact 50 is operated near the cathode 34 it may be necessary to apply a positive potential to the control electrode 38 with respect to ground. The circuit shown in Figure 2 operates in a manner substantially identical to the operation of Figure 1, the average potential of the cathode 36 being controlled by the position of the movable contact 50 in order to introduce varying degrees of compensating current into that portion of the potentiometer resistance between movable contact 50 and the grounded end of the potentiometer. By making the potential of the biasing source 55 adjustable and by means of the movable contact 50 varying degrees of compensating effects may result.

A still further modification is shown in Figure 3 and in this figure as in Figure 2 elements which are identical to the elements shown in Figure 1 bear the same reference numerals. In this modification, the cathodes 34 and 36 are connected together by means of a resistance 55 and the control electrode 38 is connected to ground by resistance 54. A condenser 56 is connected between control electrode 38 and cathode 34 in order to permit the control electrode 38 to respond to the relatively slow potential variations only. Furthermore, a resistance 41 is connected between the anodes 40 and 42 in order to eliminate any possibility of parasitic oscillations. For best operation of the circuit shown in Figure 3 it is preferable to make the resistance 55 adjustable in order that the ratio of resistance 55 to potentiometer resistance 44 may be manually controlled. The resistance 44 carries the cathode current to both of the cathodes 34 and 36 whereas resistance 55 is traversed only by current to cathode 36. By properly proportioning the values of cathode resistance 44 and 55, therefore, it is possible to vary the effects and the amount of correction produced by the correction triode. In general, the circuit shown in this modification operates substantially the same as the circuit shown in Figure 1 except that the manner in which the effectiveness of the tube is controlled is somewhat different.

A still further modification of the present invention is shown in Figure 4 wherein the correction of the direct current insertion together with the provision for affording a low impedance output in the picture signal series is accomplished in one and the same electron stream. The tube 74 includes a cathode 76, a first control electrode 78, a second control electrode 80 and an anode 82. The anode 82 is connected to a terminal 46 to which a positive potential is applied whereas the cathode 76 is connected to ground by way of potentiometer resistance 84. The control electrode 78 is connected to movable contact 50 by way of resistance 54 while the same control electrode is connected to the cathode 76 by way of condenser 56. The tube also includes screen and suppressor electrodes, the screen electrodes being decoupled by means of resistance 86 and decoupling condenser 88. The output from the cathode resistance 84 is derived from the movable contact 52 through terminals 60.

When picture signals are applied to the control electrodes 78 and substantially correct direct current reinsertion is applied, a voltage drop is produced across cathode resistance 84. A certain portion of this voltage drop is then applied to the control electrode 80 to vary the average potential of the control electrode 80 with respect to cathode 76. This slow variation in the potential of con-

trode electrode 38 with respect to its associated cathode thereby modifies the average amount of current that is permitted to pass through the tube with the result that the potential drop across resistance 34 is altered in accordance with the direct current component of the picture signal as is the case in the circuit shown in Figure 1. The circuit shown in Figure 4 is somewhat similar to the circuit shown in Figure 1 except that a single electron stream is used and two control electrodes are provided for effecting modulation of the intensity of the electron stream.

The choice of the size of the resistance 34 and condenser 36 in each of the modifications is preferably such as to provide a time constant circuit having a time constant of the order of 0.1 to 1.0 second. The rate at which the control electrode associated with this time constant circuit is permitted to change potential is therefore relatively slow so that the modulation of the electron stream will be in accordance with the direct current component and low frequency alternating current components only, to the exclusion of more rapid potential variations which actually represent detail in the picture.

By means of one or another of the various circuits described above, it may be seen that the position of the alternating current axis of the picture signal series may be definitely and accurately controlled with respect to the potential represented by black in the picture in accordance with the true light value or background level of the television picture being transmitted. The circuits are used for compensating for inaccuracies introduced by the usual diode direct current reinserting device since theoretically it is impossible to obtain completely accurate reinsertion of the direct current component by a diode reinserting device alone. Certain refinements have been made in order to afford a more accurate insertion of the D. C. component and such circuits are, for example, shown in the United States patent of F. M. Deerhake, No. 2,302,425, issued November 17, 1942. Normally, however, the load circuit for the diode reinsertion tube is of the order of one megohm so that an appreciable error may be introduced in the insertion of the direct current level. If, however, the load impedance is increased to the order of 10 megohms the percentage of error is reduced, however, it is not completely eliminated. It is, however, sometimes disadvantageous to use high impedance load circuits so that with the present invention it is possible to use a load impedance of the order of one megohm and still assure proper reinsertion of the direct current component irrespective of the background level of the picture under consideration.

The apparatus represented schematically by the reference numeral 48 has been described and referred to as a diode direct current re inserter. It is possible, however, that this element may take the form of the so called "clamp" direct current re inserter. An example of a "clamp" circuit for reinserting the direct current component, as well as a clear and concise description of such an apparatus is to be found in Collard U. S. Patent No. 2,284,085, issued on May 26, 1942. The present invention may be used to assure proper reinsertion of the direct current component where the initial reinsertion is performed by a "clamp" circuit in place of a diode or peak rectifier.

In all of the figures showing the various forms of the present invention the output circuit is shown connected to the cathode resistance. Such a connection would supply signals for applica-

tion to a low impedance translating device. If, however, it is desired to supply signals to a high impedance translating device then it would naturally follow that the signals could be derived from the anodes 40 and 42 of tube 32 or from the anode 82 of tube 14. Under these circumstances an anode load impedance would, of course, be used.

Although the present invention is described in more or less detail, it is to be understood that various alterations and modifications of the present invention may become apparent to those skilled in the art and it is desirable that any and all such modifications and alterations be considered within the purview of the present invention except as limited by the hereinafter appended claims.

What I claim is:

1. A television transmitting apparatus wherein a television image signal series is generated which at spaced intervals assume a value equal to the threshold value of the "blacker than black" region, comprising an amplifier incapable of transmitting direct current for amplifying the alternating current components of said image signals, means at the output side of said amplifier responsive to the peak values of said "blacker than black" interval signals for reinserting a fraction of the direct current component into said image signal series, and a direct current amplifier responsive to the fractionally reinserted direct current component for completing the reinsertion of the direct current component.
2. A television transmitting apparatus wherein a composite series of signals including television image signals interspersed with synchronizing impulses are supplied, the intensity of the synchronizing impulses being substantially uniform, comprising an amplifier for amplifying the alternating current component of the composite series of signals, said amplifier being incapable of transmitting the direct current and low frequency alternating current components, means at the output of the amplifier for initially positioning the alternating current axis of the amplified signals with respect to "black" by partial reinsertion of the direct current and low frequency alternating current components, and a direct current amplifier responsive to the partially reinserted direct current and low frequency alternating current components for accurately positioning the alternating current axis with respect to "black."
3. A television transmitting apparatus wherein in a series of television image signals interspersed with synchronizing impulses are supplied, the intensity of the synchronizing impulses being substantially uniform, comprising an amplifier for amplifying the alternating current component of the image signals and synchronizing impulses, said amplifier being incapable of transmitting the direct current component, means at the output of the amplifier for initially shifting the zero axis of the alternating current component with respect to "black" by partial reinsertion of the direct current component, and a direct current amplifier responsive to the partially reinserted direct current component for accurately positioning the zero axis of the alternating current component with respect to "black."
4. A television transmitting apparatus wherein in a series of television image signals interspersed with synchronizing signals are generated, the intensity of the synchronizing signals being substantially uniform, comprising an amplifier for amplifying the alternating current component of

the image signals and synchronizing signals, said amplifier being incapable of transmitting the direct current component, means at the output side of the amplifier for initially shifting the zero axis of the alternating current component with respect to a reference potential by partial reinsertion of the direct current component, and a direct current amplifier responsive to the initially shifted alternating current axis for completing the reinsertion of the direct current component to thereby accurately position the zero axis of the alternating current component with respect to the reference potential.

5. A television transmitter wherein a composite series of television image signals and synchronizing impulses interspersed therewith are supplied and where the polarity of the synchronizing impulses is opposite to that of the image signals, comprising means for amplifying the alternating current component of the image signals and synchronizing impulses, said amplifying means being incapable of transmitting direct current and low frequency alternating current components, means responsive to the peaks of impulse maxima in one direction to supply a portion of the missing direct current and low frequency alternating current components, and a direct current amplifier responsive to the reinserted direct current component portion for completing the reinsertion of the direct current and low frequency alternating current components.

6. A television transmitter wherein a composite series of television image signals and synchronizing impulses interspersed therewith are supplied and where the polarity of the synchronizing impulses is opposite to that of the image signals, comprising means for amplifying the alternating current component of the image signals and synchronizing impulses, said amplifying means being incapable of transmitting the direct current and low frequency alternating current components of the composite series, means responsive to the peaks of impulse maxima of a predetermined polarity to reinsert a portion of the missing direct current and low frequency alternating current components, and a direct current

coupled electron emissive means responsive to the reinserted portion of the direct current component for completing the reinsertion of the direct current and low frequency alternating current components.

7. A television transmitter wherein a composite series of television image signals and synchronizing impulses interspersed therewith are supplied and where the polarity of the synchronizing impulses is opposite to that of the image signals, comprising means for amplifying the alternating current component of the image signals and synchronizing impulses, said amplifying means being incapable of transmitting the direct current and low frequency alternating current components of the composite series, means responsive to the peaks of impulse maxima in a predetermined direction to reinsert a portion of the direct current and low frequency alternating current components into the composite series, and means responsive to the reinserted portion of the direct current component for completing the reinsertion of the direct current and low frequency alternating current components into the composite series.

8. A television transmitter wherein television image signals and synchronizing impulses interspersed therewith are generated and where the polarity of the synchronizing impulses is opposite to that of the image signals, comprising means for amplifying the alternating current component of the image signals and synchronizing impulses, said amplifying means being incapable of transmitting direct current and low frequency alternating current signal components, means responsive to the peaks of impulses of the polarity of the synchronizing impulses to reinsert a portion of the missing direct current and low frequency alternating current signal components, and a direct current coupled electron emissive device responsive to the reinserted direct current component portion for completing the reinsertion of the direct current and low frequency alternating current components.
